UNITED STATES PATENT OFFICE

2,240,161

OIL BURNER

Moritz L. Mueller, Grosse Pointe, Mich., assignor
to Borg-Warner Corporation, Chicago, Ill., a
corporation of Illinois

Application November 5, 1938, Serial No. 238,981

3 Claims. (Cl. 158—4)

This invention relates to oil burners, more particularly to pressure oil burners, and has special reference to an expansion chamber for accommodating sudden increases in pressure.

It is an object of this invention to provide a novel form of pressure oil burner which will be safer in operation.

It is another object of this invention to provide an oil burner which will be free from back-firing and the evil known as "flutter draft."

It is another object of this invention to provide a baffle for a pressure oil burner, which is adapted to accommodate sudden increases in pressure in the combustion chamber due to the sudden ignition of a quantity of oil and air.

My invention deals with a new combustion chamber head for oil burners. The device comprises two spaced walls through which the burner mouth is inserted. The inner one of these two walls does not tightly embrace the burner mouth so as to provide a passageway around the burner through which the rapidly expanding products of combustion at the initiation of combustion may pass, to relieve the pressure caused by the sudden ignition of the oil and air. In order for this to take place, the outer wall has vents to the atmosphere, so that some of the air which is between the two walls will be pushed out into the atmosphere when the burner is started. After conditions are stabilized, the products of combustion which have expanded into the space between the two heads are drawn back into the burner by the slight suction which will exist within the combustion chamber. During the continuation of combustion, a small supply of air will be sent into the combustion chamber through the aperture in the outer wall of the double head and around the burner mouth.

The drawing which illustrates my invention, of which there is one sheet, may be generally described as follows:

Fig. 1 is a vertical section through an oil burning furnace embodying my invention;

Fig. 2 represents an enlarged view of a portion of the combustion chamber shown in Fig. 1, the view being in vertical section to illustrate the relation of the parts; and

Fig. 3 represents an elevation of the combustion chamber head and is a view taken along the section line 3—3 of Fig. 2.

As illustrated in Fig. 1, my oil burner consists of a casing 10 of any suitable metal construction which encloses a blower compartment 12, an oil burner compartment 14, a combustion chamber 16, and a heat exchange chamber 18. The

cabinet has an opening 20 in the top thereof, through which air is supplied to the blower chamber, and an opening 22 in the top, through which warm air is directed into the heating system of the house. The cabinet may be provided with a door 24, through which access may be had to the blower or oil burner for servicing the same.

The oil burner compartment 14 is separated from the blower compartment 12 by a partition 10 26 and contains an oil burner 28 of the pressure type, having a burner mouth 30 extending into the combustion chamber 16. The oil burner may be supported on legs 32 to maintain it at the correct height above the bottom of the furnace. 15 The partition 26 supports a blower 34 and a motor 36 for operating the blower which directs air into the heat exchange compartment 18.

The heat exchange chamber 18 contains an annular flue 37 defined by an outer cylinder 38 20 and an inner cylinder 39. The flue is attached to the combustion chamber 16 at 40 and contains the spiral baffle 42, which directs the products of combustion in a spiral path through the annular flue, as is indicated by the wide line arrows. 25 The smoke pipe 44 is attached to the flue at its upper end and directs the products of combustion from the flue through the casing 10 and to the stack (not shown). The flue 37 is supported on the combustion chamber by the neck 46 which forms a connection with the combustion chamber and by a bracket 48 which supports the opposite side of the flue. The foregoing structure is disclosed and claimed in my Patent No. 2,172,399, issued September 12, 1939.

35 The combustion chamber 16 is composed of a metal cylinder 50 and contains a flame chamber 52 composed of blocks of refractory material 54. The combustion chamber 16 may also contain a connection 56 for a hot water heating coil 58. The cylinder is supported above the floor of the furnace by legs 60, so that the blast of air from the blower 34 may pass around and underneath the cylinder 50. In operation, the air from the blower 34 takes a spiral path around the outside of 40 the flue 37, and after passing down and around the cylinder 50, passes up and through the center of the annular flue 37 and out the opening 22 into the heating system of the house, as is shown by the double line arrows. A tank 62, which contains water for increasing the humidity of the air blown through the furnace, may be positioned at the rear end of the combustion cylinder 50.

45 The head for the combustion chamber 16 is more clearly illustrated in Fig. 2, which shows the combustion cylinder 50 and the end of the

flame chamber 52. The flame chamber 52 is composed of a horizontal metal cylinder 63, lined with the refractory material 54. The forward end of the flame chamber is closed by a disc of refractory material 64, having a hole 66 in the center thereof. The head for the cylinder 50 is composed of a metal disc 68, which is fastened to the cylinder 50 by the clips 70, which are bolted to the cylinder 50. The clips 70 may be fastened to the disc 68 by any suitable means, such as welding. The disc 68 has a hole which is in alignment with the hole 66 in the forward end of the flame chamber and through which the burner mouth 30 is adapted to be inserted. An annular bracket 72 may be bolted around the hole in the disc 68 for the purpose of maintaining the burner mouth 30 in its correct position. Fastened to the side of disc 68 toward the inside of the combustion chamber is a second plate 76, which is spherical in shape and is drawn down tight against the plate 68 by means of the bolts 74.

The spherical plate 76 has a circular flange 78 raised from its back side in such a manner that the plate may be sealed against the end of the flame chamber, thus forcing any gases which pass through the hole 66 to pass through the hole 80 in the spherical plate 76. Both the hole 66 and the hole 80 are of larger diameter than the burner mouth 30, which passes through both holes and thus leaves an annular passage around the burner mouth, between the flame chamber 52 and the space between the head plates 68 and 76. This space between the two plates is open to the atmosphere of the oil burner chamber 14 through two ports 82, which may be closed or regulated by the dampers 84 bolted to the plate 68. It should be noted that the contacts between the plate 68 and the combustion cylinder 50 are sealed so that no gases may pass therebetween. There is also a sealed connection between the plate 68 and the plate 76 and between the plate 76 and the head of the flame chamber, where the burner mouth passes through those members. The burner mouth is also sealed to the plate 68, where it passes through the plate. In this manner, the only passage for gases between the combustion chamber and the atmosphere of the oil burner chamber is through the hole 66, hole 80, and then through the ports 82.

In operation, the oil burner 28, which may be any conventional pressure type burner and which I have illustrated as having a burner head 86 and nozzle 88, will pump a stream of finely divided oil and air into the flame chamber 52. The mixture may be ignited by any means such as the electrodes 90. Just before ignition takes place, there will be a relatively small pressure in the flame chamber. At the time of ignition, there will be a sudden increase in the pressure within the combustion chamber and flame chamber, due to the sudden expansion of this mixture of oil and air. This increase in pressure may work its way out partly through the flue 37 and partly through the holes 66 and 80 into the space between the plates 68 and 76. The air within the space between the head plates may escape through the ports 82, thus relieving the suddenly

increased pressure within the combustion chamber. The space between the plates 68 and 76 may be made large enough so that no gases will be forced out of the ports 82, the only displacement being that of the air that is already in the space between the two plates. As soon as the combustion is well started, the blast from the burner mouth and the draft created by the warm gases in the combustion chamber will draw all of the gases out of the flame chamber into the combustion chamber proper and out through the annular flue 37, and there will be no tendency for the burning gases to escape through the head of the combustion chamber. A small supply of secondary air may even be drawn in through the ports 82 and through the passage 66 around the burner mouth, due to the draft set up in the combustion chamber. This arrangement of parts allows for the sudden expansion of gases, due to ignition, in the combustion chamber without the necessity of a complicated system of expandible chambers or expansion valves.

While I have described my invention with some detail, I intend it to be for the purpose of explanation only and reserve the right to make such changes in the structure as will fall within the purview of the attached claims.

I claim:

1. In combination with a furnace having a combustion chamber and a pressure oil burner operatively associated therewith and adapted to supply a combustible mixture of oil and air to said combustion chamber, a pair of heads constructed and arranged so as to define an expansion chamber and situated so as to close one end of said combustion chamber, a restricted communication between said chambers independently of said oil burner, said expansion chamber having a port communicating directly with the atmosphere outside of said oil burner and said combustion chamber.

2. In combination with a furnace having a combustion chamber and a pressure oil burner operatively associated therewith and adapted to supply a combustible mixture of oil and air to said combustion chamber, an expansion chamber formed in part by a wall of said combustion chamber, a restricted communication between said chambers independently of said oil burner, said expansion chamber having a port remote from said restricted communication and communicating directly with the atmosphere outside of said combustion chamber.

3. In combination with a furnace having a combustion chamber and a pressure oil burner operatively associated therewith and adapted to supply a combustible mixture of oil and air to said combustion chamber, a head cooperating with a wall of said combustion chamber so as to define an expansion chamber, a part of said burner extending through said expansion chamber, a restricted communication externally of said part of said burner and between said chambers, said expansion chamber having a port communicating directly with the atmosphere outside of said combustion chamber.

MORITZ L. MUELLER.
